UNITED STATES PATENT OFFICE

2,253,197

FLUID BLAST CIRCUIT BREAKER

David C. Prince, Swarthmore, Pa., assignor to
General Electric Company, a corporation of
New York

Application November 3, 1938, Serial No. 238,631

3 Claims. (Cl. 200—148)

My invention relates to fluid blast circuit breakers, more particularly to gas blast circuit breakers, and has for its principal object the provision of an improved gas blast circuit breaker wherein a source of stored blast energy, such as spring energy for example, is utilized in combination with an independent source of pressure for effecting arc interruption under all operating conditions.

The commercial use of gas blast circuit breakers has been retarded to a certain extent by the possibility of failure of the gas pressure supply when it is desired to interrupt a heavy over-load or short circuit current. In such cases opening of the breaker contacts in the absence of an adequate gas blast might result in destruction of the breaker as well as further damage wherein an indoor station is involved.

In accordance with my invention such a hazard is greatly minimized by storing a pre-determined amount of blast energy, such as by a spring charging operation, and by utilizing this energy upon failure of the main pressure source both to open the breaker contacts and to supply an effective gas blast for arc interruption. Therefore, in the case of failure of the main pressure source, the breaker automatically opens and the arc is interrupted by a gas blast in the usual manner. With this arrangement the stored blast energy is also utilized for normal current interruptions so that the main pressure source can be most economically used.

My invention will be more fully set forth in the following description referring to the accompanying drawing, and the features of novelty which characterize my invention will be pointed out with particularity in the claims annexed to and forming a part of this specification.

Referring to the drawing the single figure thereof is an elevational view, partly in section and partly diagrammatically shown, of a gas blast circuit breaker embodying the present invention.

The circuit breaker, as shown, is of the transverse or cross blast type and comprises a pair of relatively movable contacts 1 and 2 mounted within an insulating casing 3 which forms a blast passage 4 through which gas under pressure is directed transversely of the arc path between the contacts.

The gas blast exhausts through a diverging arc chute 5 having insulating arc splitters 6 for purposes well known in the art. The contact 1 is fixed within the casing 3 at one side of the blast passage and is connected to one of the breaker terminals 1'. The coacting contact 2 with its extension is guided for reciprocal movement in the opposite side of the casing 3 and is likewise suitably connected to the opposite breaker terminal 2'. The contact 2 is normally

biased by a spring 7 toward open circuit position, the spring being seated between a piston 8 and its cylinder 9. The contacts may also be provided with short diverging arc runners 1a and 2a respectively.

The piston 8 is connected to and movable with the contact 2 so that in combination with the spring 7 it has a double function in both closing the breaker when gas under pressure is admitted 10 to the cylinder head at 10 and also creating a gas blast during the opening operation. During the circuit closing operation, the spring 7 is placed under tension and is held in charged position by gas pressure within the cylinder 9. The piston and cylinder therefore serve in effect at 15 this stage as an expansible reservoir for blast energy.

When this energy is released the breaker is 20 opened and the piston 8 delivers a gas blast from the cylinder 9 to the arc passage 4 by way of the conduit 11. A blast control valve 12, normally biased by a spring 13 to close the blast 25 passage 4, as illustrated, is opened to admit the blast to the contacts in a manner presently described.

The main source of gas pressure, such as a 30 tank and compressor for example, for operating the circuit breaker is generally indicated at 14 and is connected through a breaker control valve 15, to the blast valve housing 16. The valve housing 16 is provided with a bypass 17 communicating with the conduit 11 through a non-return valve 18. As illustrated, the valve 18 is 35 closed except when the pressure in the bypass exceeds that in the conduit 11.

The operation of the circuit breaker is as follows: Assuming that the breaker is in the open circuit position illustrated and that it is desired to close the same, the valve 15 is actuated in any 40 suitable manner, as by an operating solenoid 19 and a remote control switch 20 to connect the main pressure source at 14 with the valve housing 16. This is accomplished in the present instance by reciprocal movement of a plunger valve 45 comprising a pair of cylindrical valve members 15a and 15b. The valves 15a and 15b are interconnected by a reduced valve stem 15c arranged so that as the plunger valve is operated by solenoid 19 against the bias of a spring 21, it uncovers the valve port at 22. In this operation 50 the valve member 15b also closes the exhaust port at 26.

Gas under pressure is accordingly delivered 55 to the main valve housing 16 from where it is directed through the bypass 17 to the cylinder 9 to close the breaker. The contact 2 remains closed as long as gas pressure is maintained at the piston 8. It will be noted that when the valve 15 is in the open position, the valve portions 15a and 15b function as pistons which are 60

acted upon by the main gas pressure for holding the valve in the open position against the bias of spring 21.

In view of the fact that the pressure at opposite sides of the valve 12 is normally equalized by reason of the bypass 17, a comparatively light spring at 13 is effective to maintain the blast passage 4 closed, as illustrated. When the valve 15b is closed as shown, it should tightly seal that end of the valve casing, as otherwise the gas pressure from 14 might force the valve open. In case of gas leakage, however, a pin hole vent can be provided at the end of the casing which 15b abuts to overcome this difficulty.

The opening operation of the circuit breaker, as in response to an overload or short circuit on the line, can be accomplished by the usual current transformer 23, in combination with a relay 24, for energizing a second valve operating solenoid 25. The valve 15 is thereupon operated to the closed position against the gas pressure. In this position the valve housing 16 is directly vented as shown to atmosphere at 26. The pressure differential resulting from release of pressure at the lower side of the valve 12 causes depression of the valve against the bias of spring 13 and opening of the blast passage 4. The charged spring 1 is thereupon released to cause opening movement of the contact 2 and piston 8 and return of the stored blast energy through the conduit 11 to the blast passage 4 where the resulting blast interrupts the arc. It should be noted that the full blast pressure is instantly available even before movement of the piston 8 is initiated. The piston, however, serves to sustain the blast. In the type of air blast breaker relying solely on a piston, it has been found that the piston must travel an appreciable part of its stroke before the proper blast pressure is obtained.

At the instant of initial separation, the contacts 1 and 2 are separated by a very short gap. However, the tips of the arc runners 1a and 2a are separated by a large gap. The gas blast will immediately transfer the arc to the tips of the arc runners, thereby lengthening the arc to such an extent that it can readily impinge on the arc splitters 6. Accordingly, even before the original arc gap has lengthened to the extent ordinarily required, the arc may be extinguished at the splitters. By reason of the higher pressure and the correspondingly high dielectric strength of the gas blast at the original gap, restriking of the arc is less probable after the arc has been interrupted at a current zero. This is particularly important in high voltage breakers where restriking of the arc due to recovery voltage may be encountered.

During the arc interrupting blast, which coincides with the separation of the contacts, the non-return valve 18 is closed and the entire blast is directed past the valve 12 and through the arc path. The breaker reclosing operation is accomplished in the manner above described.

Assuming now that the breaker is in the normally closed circuit position, and that the main gas pressure source fails, the stressed valve spring 21, when the gas pressure drops sufficiently, will close the valve 15 to cause tripping of the breaker and arc interruption in the manner above described. Even in the event that the valve 15 fails to function properly, the drop in pressure within the valve housing 16 would accomplish the same result, since the unbalanced pressure at the valve 12 would cause opening of the same 75

to release the blast energy stored in the cylinder 9.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. A gas blast circuit breaker comprising separable contacts, means forming a blast passage to said contacts, means for storing blast energy comprising a spring biased piston operatively connected to said contacts, a main source of gas pressure, a valve for controlling communication between said source and piston for closing said breaker and storing said blast energy, said valve being normally maintained in open position by gas pressure from said source, means biasing said valve toward closed position upon decrease of said source pressure, a mechanically separate blast control valve independent of said first-named valve for controlling communication between said piston and said blast passage, means for maintaining said blast valve normally closed, and electromagnetic means associated with said first valve for releasing pressure at one side of said blast control valve when said first valve is closed for causing opening of said blast valve thereby releasing a gas blast through said passage under influence of said stored blast energy.

2. A gas blast circuit breaker comprising separable contacts, means forming a blast passage to said contacts, means for storing blast energy comprising a spring biased piston operatively connected to said contacts, a main source of gas pressure, a valve for controlling communication between said source and piston for closing said breaker and storing said blast energy, said valve being maintained in open position by gas pressure from said source, means biasing said valve toward closed position upon decrease of said source pressure, a blast control valve for controlling communication between said piston and said blast passage, spring means for maintaining said blast valve normally closed, means associated with said first valve for releasing pressure at one side of said blast control valve when said first valve is closed for causing opening of said blast valve thereby releasing a gas blast through said passage under influence of said stored blast energy, control means for operating at will said first valve, and spring means for biasing said first valve against said source pressure toward the aforesaid pressure releasing position whereby failure or predetermined decrease of said source pressure results in operation of said first valve by said spring.

3. A gas blast circuit breaker comprising separable contacts, means forming a blast passage to said contacts, means for storing blast energy including a gas reservoir, a blast valve for controlling admission of gas from said reservoir to said blast passage, a main source of gas pressure, and a second mechanically separate valve means independent of said blast valve for controlling communication between said source and said reservoir to permit storage of blast energy in said reservoir, means forming a gas passage communicating with said blast valve, said second valve means also being separately operable to open said last mentioned gas passage to cause opening of said blast valve.

DAVID C. FRINCE.
